Primary Examiner — Susan E Krakower*Assistant Examiner* — Jerry Shiuan-Hua Hsu(74) *Attorney, Agent, or Firm* — Millen, White, Zelano & Branigan, P.C.; William Nixon(57) **CLAIM**

The ornamental design for a trailer, as shown and described.

DESCRIPTION

FIG. 1 is a perspective view of a trailer showing our new design;

FIG. 2 is a left side elevational view of the trailer;

FIG. 3 is a right side elevational view of the trailer;

FIG. 4 is a front elevational view of the trailer;

FIG. 5 is a rear elevational view of the trailer;

FIG. 6 is a top plan view of the trailer; and,

FIG. 7 is a bottom plan view of the trailer.

The broken lines depict portions of the trailer and form no part of the claimed design.
